Saverys

United States Patent Office.

WILLIAM HENRY WOODS, OF SAN FRANCISCO, CALIFORNIA.

Letters Patent No. 63,684, dated April 9, 1867.

IMPROVEMENT IN BIT-BRACES.

The Schedule referred to in these Letters Patent and making part of the same.

TO ALL WHOM IT MAY CONCERN:

Be it known that I, WILLIAM HENRY Woods, of San Francisco city, San Francisco county, State of California, have invented a new and improved "Bit-Brace;" and I do hereby declare the following description and accompanying drawings are sufficient to enable any person skilled in the art or science to which it most nearly appertains to make and use my said invention without further invention or experiment.

The nature of my invention is to provide an improved bit-brace so constructed that the bit may be easily and securely fastened to the stock, and the wear between the stationary and movable parts may be compensated for, and also much lessened. To accomplish these ends the brace has a slot cut in the side at the lower extremity, within which moves a key turning on a pivot at its upper end. A collar, the inside of which is eccentric, surrounds the shaft of the brace and the key, and by simply turning it partly around forces the key into the depression in the head of the bit. At the upper end of the brace is an opening, in which is placed a small steel pin, which also fits loosely in the head. Both ends of this pin turn on a steel die, and any wear is compensated by a check-nut, which can be moved at pleasure as necessity requires.

In order to more fully explain the working of my invention, reference is had to the accompanying drawing and letters marked thereon, of which—

Figure 1 is a side sectional elevation.

Figure 2 is an end view of the lower end of the brace showing the cam.

Figure 3 is a view of the collar.

Similar letters indicate like parts in each of the figures.

A is a brace of my construction, having at its lower end, on one side, a slot, in which is placed the key *a*. This key turns on the pivot *e*, and has a projection, *b*, at its lower extremity. B is a collar which surrounds the lower part of the brace, and is kept in place by the nut *c*. Its lower part is formed into the shape of an eccentric-cam, as shown at *d*. By turning this collar the cam presses against the projection *b*, and forces a similar one on the inside into the depression in the head of the bit. The upper end of the brace consists of the head *C* and the hollow cylinder or collar *D*, in which is a cylindrical block, *E*. The head *C* is fastened to *E* by the screw *F*. A hole in the lower end of *E* receives a small steel step, *m*, on which turns one end of the pin *g*. A similar step is placed in the body of the brace at *n*, supporting the other end of the pin. *G* is a check-nut, which is turned up against the collar *D*, so that all the pressure and wear may come on the pin *g* and the two steel steps. By moving this check-nut, when the pin is worn down, the other parts are saved from the friction, and are so regulated that the wear comes on the pin all the time. By using the eccentric-cam to fasten the bit in place this end is accomplished more thoroughly, and the slot or groove in the end of the bit may be made very shallow.

Having thus described my invention, what I claim, and desire to secure by Letters Patent, is—

The brace head, consisting of the collar *D*, the block *E*, the pin *g*, and the steps *m* and *n*, with the nut *G*, substantially as and for the purpose described.

In witness whereof I have hereunto set my hand and seal.

WILLIAM H. WOODS. [L. S.]
